(57) **ABSTRACT**

The present invention provides a golf club shaft. The shaft is made of a fiber reinforced resin. When a position 100 mm apart from a distal end of the shaft is represented by P1, a position 200 mm apart by P2, a position 500 mm apart by P3, and a position 1,000 mm apart by P4, thicknesses at the positions are defined as P1: not more than 1.0 mm, P2: not more than 0.9 mm, P3: not more than 0.6 mm and P4: not more than 0.6 mm. Each section between the positions has a thickness larger than a thickness transition obtained by connecting the thicknesses at the positions by a straight line. The shaft includes a plurality of prepregs which include first prepregs containing carbon fibers and a second prepreg containing a high specific gravity material.

FIG. 1

FIG. 2

1
GOLF CLUB AND SHAFT

BACKGROUND OF THE INVENTION

1. Field of the Invention

The present invention relates to a golf club and a shaft thereof and, more particularly, to a shaft made of a fiber reinforced resin and a golf club including the shaft.

2. Description of the Related Art

A carbon shaft is widely used as a golf club shaft made of a fiber reinforced resin. The carbon shaft is made of a fiber reinforced resin containing carbon fibers as main fibers. As a method of manufacturing the carbon shaft, a sheet winding method is known (Japanese Patent Laid-Open Nos. 2002-35185 and 2007-190107). In this manufacturing method, a prepreg sheet is wound around a mandrel (cored bar), and a wrapping tape is further wound. After that, the prepreg is hardened by heating, thereby manufacturing a shaft.

In general, a golf club shaft made of FRP mainly includes a straight layer in which fibers are arranged almost in parallel to the shaft axis and an angle layer in which fibers are arranged obliquely with respect to the shaft axis. A reinforcing layer is further added to the periphery on the distal end side (head side) or on the proximal end side in some cases. For example, Japanese Patent Laid-Open No. 2002-35185 describes a shaft in which a prepreg made of a metal fiber reinforced resin is arranged only on the head attachment side including a portion in contact with the end face of the neck.

FRP has a high specific strength and a high specific modulus and is therefore suitable for weight reduction of a shaft. When the shaft is made light, the whole golf club becomes light. For this reason, the so-called head speed at swing (the speed of the golf club head portion at the instant of ball impact) increases, and a longer distance can be attained.

Weight reduction of the shaft improves the head speed and increases the distance. On the other hand, since the load that the golfer feels in swing is too small, the swing may be unstable, or the golfer may feel as if his/her physical powers were not sufficiently exerted.

For example, Japanese Patent Laid-Open No. 2007-190107 describes a shaft that adds a mass of about 1 to 5 g near the point of center of gravity of the shaft by, for example, enfolding a metal fiber reinforced resin prepreg, thereby improving the sensation or impression of a golfer such as a weight and rigidity while suppressing increases in the physical amounts such as a mass and a moment of inertia.

If the metal fiber reinforced resin prepreg is wound to weight only on the head attachment side including the portion in contact with the end face of the neck, as in Japanese Patent Laid-Open No. 2002-35185, the hitting feel or swing-through feel degrades, and the weight balance of the shaft becomes poor. When only the head attachment side including the portion in contact with the end face of the neck is weighted, the head can be light to keep the balance of the golf club. However, if the head is made light, the initial speed of a hit ball lowers.

In the shaft that weights near the point of center of gravity, as in Japanese Patent Laid-Open No. 2007-190107, the increase in the moment of inertia caused by addition of the weight is small. If the weight amount is increased to obtain a sufficiently large moment of inertia, the shaft becomes heavy and hard to swing.

2
SUMMARY OF THE INVENTION

It is an object of the present invention to provide a shaft having a large moment of inertia, easy to swing, and having a satisfactory swing-through feel, and a golf club including the shaft.

According to an aspect of the present invention, there is provided a shaft for a golf club, which is made of a fiber reinforced resin, wherein when a position 100 mm apart from a distal end of the shaft is represented by P1, a position 200 mm apart by P2, a position 500 mm apart by P3, and a position 1,000 mm apart by P4, thicknesses at the positions are defined as

- P1: not more than 1.0 mm
P2: not more than 0.9 mm
P3: not more than 0.6 mm
P4: not more than 0.6 mm

each section between the positions has a thickness larger than a thickness transition obtained by connecting the thicknesses at the positions by a straight line, the shaft comprises a plurality of prepgs, the plurality of prepgs include a plurality of first prepgs and at least one second prepg, the plurality of first prepgs comprise prepgs containing carbon fibers, the second prepg comprises a prepg containing a material having a specific gravity higher than the specific gravity of the prepgs containing carbon fibers, and a weight of the shaft is 35 g (inclusive) to 45 g (inclusive).

According to another aspect of the present invention, there is provided a shaft for a golf club, comprising a plurality of prepgs, wherein the plurality of prepgs include a plurality of first prepgs and at least one second prepg, the plurality of first prepgs comprise prepgs containing carbon fibers, the second prepg comprises a prepg containing a material having a specific gravity higher than the specific gravity of the prepgs containing carbon fibers,

the shaft has a thickness of not more than 1.0 mm at a position 100 mm apart from a distal end,
the shaft has a thickness of not more than 0.9 mm at a position 200 mm apart from the distal end,
the shaft has a thickness of not more than 0.6 mm at a position 500 mm apart from the distal end,
the shaft has a thickness of not more than 0.6 mm at a position 1,000 mm apart from the distal end, and
a weight of the shaft is 35 g (inclusive) to 45 g (inclusive).

According to still another aspect of the present invention, there is provided a golf club including the shaft.

Further features of the present invention will become apparent from the following description of exemplary embodiments (with reference to the attached drawings).

BRIEF DESCRIPTION OF THE DRAWINGS

FIG. 1 is a view showing the thickness distribution of a section of a shaft;

FIG. 2 is an explanatory view of winding of prepgs according to an embodiment; and

FIG. 3 is an explanatory view of winding of prepgs according to an embodiment.

DESCRIPTION OF THE EMBODIMENTS

An embodiment will now be described with reference to the accompanying drawings.

FIG. 2 is an exploded view showing prepgs so as to explain a method of manufacturing a golf club shaft according to an embodiment of the present invention. In this

manufacturing method, a mandrel **10** and prepgs **11** to **20** are used. The central axis of the mandrel **10** is straight. The mandrel **10** has a circular sectional shape perpendicular to the central axis. The mandrel **10** has a tapered shape that is thin on the distal end side (head side) and thick on the proximal end side (grip side). However, the mandrel **10** may partially have an equal diameter portion with a predetermined diameter.

Preferably, after a release agent is applied to the surface of the mandrel **10**, sheet-shaped prepgs **11** to **20** are sequentially wound.

The prepgs **11** to **20** contain carbon fibers and a matrix resin. The prepg **13** further contains metal fibers or a metal powder. The metal powder is preferably a powder of a metal having a high specific gravity such as tungsten or stainless steel. The metal fibers are preferably fibers of a metal having a high specific gravity such as tungsten, stainless steel, or copper. Note that when containing metal fibers, the prepg **13** need not contain carbon fibers. The prepg **13** constructs a weighting portion. When the weighting portion is provided, it is possible to increase the moment of inertia and allow the player to feel a moderate swing weight.

In this embodiment, the prepg **12** forms an angle layer, each of the prepgs **14**, **16**, and **18** forms a straight layer, each of the prepgs **15** and **17** forms a hoop layer, and each of the prepgs **11**, **19**, and **20** forms a reinforcing layer. That is, in this embodiment, the carbon fibers in the prepgs **11**, **14**, **16**, and **18** to **20** are aligned within the range of $\pm 10^\circ$ with respect to the shaft axis direction. In the prepgs **15** and **17**, the carbon fibers are aligned at the angle (within $90^\circ \pm 10^\circ$, particularly, within $\pm 5^\circ$) of a direction almost perpendicular to the long shaft axis direction. In the prepg **12**, carbon fibers aligned at an angle of $+45^\circ$ and those aligned at an angle of -45° are used. The angle of the carbon fibers is not limited to 45° and preferably falls within the range of 30° to 60° .

The prepgs **12** and **14** to **18** have a length extending along the total length of the shaft. The prepgs **19** and **20** have a length almost 8% to 35% the total length of the shaft so as to be arranged only on the distal end side in the shaft. When the shaft is equally divided into five, first to fifth sections in the axial direction from the distal end side, the prepg **13** is preferably arranged in the first to third sections, particularly, in the first and second sections. The length of the prepg **13** in the shaft axis direction is preferably 2% or more, particularly 4% or more to 13% or less, particularly 9% or less of the shaft total length. Note that the prepg **13** is not arranged in the insertion portion to the hosel on the distal end side in the shaft.

Each of the prepgs **11** to **20** has a width so as to be wound on the outer surface of the mandrel **10** by one or a plurality of turns, for example, one to five turns.

The prepg **13** has an almost trapezoidal shape whose short sides (a side on the distal end side in the shaft and a side on the proximal end side in the shaft) are oblique with respect to the shaft circumference direction.

When the prepg **13** is arranged in the inner layer side, and the two short sides of the prepg **13** are made oblique with respect to the shaft circumference direction, steps formed on two end sides of the weighting portion in the shaft axis direction become moderate. This prevents stress concentration and attains a good outer appearance.

The prepg **13** is preferably bonded to the prepg **12** or sandwiched between two prepgs **12**. This prevents the prepg **13** from peeling during the winding operation and attains a good winding operability of the prepg.

Each of the prepgs **11** to **20** preferably has a thickness of about 0.125 mm or less. As the resin of the prepgs, epoxy resin or the like is preferable.

In FIG. 2, one prepg **13** is used. However, two or more prepgs **13**' may be used, as shown in FIG. 3. Each prepg **13**' is triangular but may have an almost trapezoidal shape formed by truncating a portion near an apex of a triangle.

In FIGS. 2 and 3, the sides of the prepgs **14** to **18** in the shaft axis direction are almost parallel on the grip side of the prepgs **14** to **18**. However, a shape as indicated by broken lines may be used. In FIGS. 2 and 3, the short side of the prepg **19** on the grip side is oblique with respect to the circumferential direction. However, a shape as indicated by broken lines may be used.

In a normal case, it is preferable to wind three to five prepgs containing fibers in the straight direction, two, four, or six prepgs containing fibers in the bias direction, and one to three prepgs containing fibers in the hoop direction.

The operation of winding the prepgs **11** to **20** on the mandrel **10** may be performed manually or using a winding machine (to be also referred to as a rolling machine). After the prepgs **11** to **20** are wound on the mandrel, a wrapping tape winding process is performed. Although not illustrated, the wrapping tape is spirally wound.

After the winding process, a hardening process is performed by heating, and the matrix resin in the prepg is hardened. After the hardening process, the mandrel **10** is pulled out, and the wrapping tape is removed, thereby obtaining a hardened tubular member (base tube). After the two ends of the base tube are cut as needed, the member is polished to form a golf club shaft.

When the shaft is equally divided into five, first to fifth sections in the axial direction, the weighting portion is preferably arranged in the first to third sections, particularly, in the first and second sections on the distal end side in the shaft except the insertion portion to the hosel. When the weighting portion is provided in such sections, the moment of inertia can be increased by increasing the weight only a little, and the player can feel a moderate swing weight. The shaft is easy to swing and has satisfactory swing-through stability. When the weighting portion is provided on the distal end side in the shaft except the insertion portion to the hosel, the weight balance of the shaft is good. It is not always necessary to reduce the weight of the head, and the initial speed of a ball does not lower.

The distance between the distal end and the front end of the weighting portion (on the distal end side in the shaft) is preferably 50 mm or more, particularly 70 mm or more to 600 mm or less, particularly 450 mm or less. The length of the weighting portion in the shaft axis direction is preferably 50 mm or more, particularly 70 mm or more to 150 mm or less, particularly 100 mm or less.

The weight of the shaft is preferably 35 g or more, particularly 37 g or more to 45 g or less, particularly 42 g or less. The weight of the weighting portion by the prepg **13** is preferably 15% or less, particularly 10% or less and 4% or more, particularly 6% or more of the shaft weight.

A preferable thickness distribution of a thus manufactured shaft will be described with reference to FIG. 1. As shown in FIG. 1, a position 100 mm apart from the distal end of the shaft is represented by P1, a position 200 mm apart by P2, a position 500 mm apart by P3, and a position 1,000 mm apart by P4. The thicknesses at the positions are

P1: 1.0 mm or less, particularly 0.95 mm or less and 0.8 mm or more, particularly 0.85 mm or more

P2: 0.9 mm or less, particularly 0.85 mm or less and 0.75 mm or more, particularly 0.8 mm or more

5

P3: 0.6 mm or less, particularly 0.55 mm or less and 0.45 mm or more, particularly 0.5 mm or more

P4: 0.6 mm or less, particularly 0.55 mm or less and 0.45 mm or more, particularly 0.5 mm or more Each section between the positions has a thickness larger than the thickness transition obtained by connecting the thicknesses at the positions by a straight line. With this thickness distribution, the shaft has a light weight and a sufficient strength.

In the golf club having this shaft, the weighting portion is arranged near the distal end of the shaft except the insertion portion to the hosel. It is therefore possible to effectively increase the moment of inertia on the proximal end of the shaft by a small weight. Although this shaft is light, the player can feel a moderate swing weight and attain stability in swing.

The stacking examples of prepgs shown in FIGS. 2 and 3 are merely examples of the present invention, and any stacking example other than those shown in FIGS. 2 and 3 is possible. In the above description, the prepgs contain carbon fibers as reinforcing fibers. Other types of fibers such as glass fibers, silicon carbide fibers, alumina fibers, aromatic polyamide fibers, or boron fibers may also be mixed.

The present invention is applicable to various kinds of golf clubs such as a wood type, utility type, iron type, and putter type and particularly suitable for a golf club whose shaft length is 40 inches (1,016 cm) or more, particularly 43 inches (1,092 cm) or more.

While the present invention has been described with reference to exemplary embodiments, it is to be understood that the invention is not limited to the disclosed exemplary embodiments. The scope of the following claims is to be accorded the broadest interpretation so as to encompass all such modifications and equivalent structures and functions.

This application claims the benefit of Japanese Patent Application No. 2014-118812, filed Jun. 9, 2014, which is hereby incorporated by reference herein in its entirety.

What is claimed is:

1. A shaft for a golf club, which is made of a fiber reinforced resin, wherein

when a position 100 mm apart from a distal end of the shaft is represented by P1, a position 200 mm apart by P2, a position 500 mm apart by P3, and a position 1,000 mm apart by P4, thicknesses at the positions are defined as

P1: not more than 1.0 mm

P2: not more than 0.9 mm

P3: not more than 0.6 mm

P4: not more than 0.6 mm

each section between the positions has a thickness larger than a thickness transition obtained by connecting the thicknesses at the positions by a straight line,

the shaft comprises a plurality of prepgs, said plurality of prepgs include a plurality of first prepgs and at least one second prepg,

said plurality of first prepgs comprise prepgs containing carbon fibers,

6

said second prepg comprises a prepg containing a material having a specific gravity higher than the specific gravity of the prepgs containing carbon fibers, and

5 a weight of the shaft is 35 g (inclusive) to 45 g (inclusive).

2. The shaft according to claim 1, wherein said plurality of first prepgs include:

a prepg arranged along a total length of the shaft and forming an angle layer, in which the carbon fibers are aligned at an angle of 30° to 60° with respect to a long axis of the shaft;

a prepg arranged along the total length of the shaft and forming a straight layer, in which the carbon fibers are aligned at an angle of $\pm 10^\circ$ with respect to the long axis of the shaft;

a prepg arranged along the total length of the shaft or along part of the total length of the shaft and forming a hoop layer, in which the carbon fibers are aligned at an angle of a direction substantially perpendicular to the long axis of the shaft; and

a prepg arranged along part of the total length of the shaft and forming a reinforcing layer, said angle layer is arranged on an inner side of said straight layer,

said hoop layer is arranged on an outer side of said angle layer, and

said second prepg is arranged in contact with said angle layer.

3. The shaft according to claim 1, wherein two sides of said second prepg in a crossing direction crossing a shaft axis direction are oblique with respect to a shaft circumference direction.

4. The shaft according to claim 1, wherein the material is metal fiber.

5. The shaft according to claim 1, wherein the material is a metal powder.

6. The shaft according to claim 1, wherein when the shaft is equally divided into five, first to fifth sections in the shaft axis direction from a distal end side, said second prepg is arranged in one of the first section or the second section except an insertion portion to a hosel.

7. The shaft according to claim 1, wherein when the shaft is equally divided into five, first to fifth sections in the shaft axis direction from a distal end side, said second prepg is arranged in one of the first to third sections except an insertion portion to a hosel.

8. The shaft according to claim 1, wherein the weight of said second prepg is not more than 15% of the weight of the shaft.

9. The shaft according to claim 1, wherein a length of said second prepg in a shaft axis direction is 50 (inclusive) to 150 mm (inclusive).

10. A golf club including a shaft of claim 1.

* * * * *
